[57] **ABSTRACT**

An adjustable recline-control mechanism for furniture of the type comprising a carrier for an occupant, e.g. a seat-pan and a support e.g. a back-rest, reclinable relative to the carrier wherein the angle of recline is controlled by the mechanism which comprises a link one

end of which is pivotally connected to the support while the other end is latchable by at least two cooperating latching portions which respectively prevent travel of the link in opposite directions, the respective latching portions being spaced apart relative to the pivot axis of the link such that a jolt to the front or back of the support exerts on the link a moment which biases the link towards latching irrespective of the direction of the jolt. Each latching portion suitably comprises a fixed toothed array and a cooperable displaceable tooth array, at least one tooth in each array comprising a thrust face and the teeth being arranged so that projections normal to a thrust face in each of the latching portions pass respectively on opposite sides of the pivot axis of the link. The mechanism is suitably incorporated into furniture, especially a motor vehicle seat, and is of utility in household and garden furniture.
